E. F. WEMHOENER,
VACUUM CLEANER,
APPLICATION FILED OCT. 13, 1916.

1,263,299.

Patented Apr. 16, 1918.

UNITED STATES PATENT OFFICE.

EMIL F. WEMHOENER, OF ST. LOUIS, MISSOURI.

VACUUM-CLEANER.

1,263,299.

Specification of Letters Patent. Patented Apr. 16, 1918.

Application filed October 13, 1916. Serial No. 125,377.

To all whom it may concern:

Be it known that I, EMIL F. WEMHOENER, a citizen of the United States of America, and a resident of the city of St. Louis, in the 5 State of Missouri, have invented certain new and useful Improvements in Vacuum-Cleaners, of which the following is a full, clear, and exact description, reference being had to the accompanying drawing, forming a part 10 of this specification.

My invention relates to a vacuum cleaner suitable for use in removing dirt or other small particles of substance from locations not readily accessible, the invention being 15 more particularly intended for use in cleaning the tracker bars of player pianos.

The cleaner comprises a cylinder containing a piston and piston rod operable therein, the piston having a spring-seated valve 20 permitting passage of air through the piston in one direction only; and the cylinder having a spring-seated valve in one end of the cylinder preventing the exit of air through that end of the cylinder, a screen seating 25 within that end of the cylinder, a suction chamber provided with a cushioned intake nipple, and a band clamp securing the suction chamber to the cylinder and the screen between them.

30 Figure I is a side elevation of my vacuum cleaner.

Fig. II is a longitudinal axial section through the cleaner shown as it appears when applied to a tracker bar.

35 Fig. III is an enlarged view of the forward portion of the cleaner shown partly in elevation and partly in section.

Figs. IV, V and VI are cross sections taken respectively on lines IV—IV, V—V, 40 and VI—VI, Fig. II.

In the accompanying drawings, A designates the cylinder of my vacuum cleaner which comprises a tube 1, a cap 2 at the rear end of the cylinder, and a head 4 at the 45 front end of the cylinder. The cap 2 is provided with one or more air vents 3.

The head 4 is intermediately provided with an apertured interior diaphragm 5, through which air may pass to enter the 50 cylinder, the passage of air through said diaphragm being controlled by a suction valve 6 which seats against the rear side of the diaphragm, as seen in Fig. III. The valve 6 is normally held seated against the 55 diaphragm 5 by a spring 7 surrounding a pin 8 mounted in the diaphragm, and about

which the valve 6 is loosely fitted. The head 4 is also provided on its rear side with a screw-threaded counterbore 4^a adapted to receive a washer and the adjacent end of the 60 tube 1, and at the opposite side with a counterbore 4^b adapted to receive washers and a screen 21, this side of the head 4 being also provided with an external screw thread adapted to receive a clamping band 16 pro- 65 vided with an inturned flange 17 engaging an annular rib 18 on a suction chamber 15, having a rim adjacent the screen when assembled. When the band 16 is screwed home the screen is tightly secured between 70 the head 4 and the rim of the suction chamber. 9 designates a piston rod loosely arranged in the cap 2 of the cylinder A and adapted to be reciprocated therein. 10 is a piston operable to and fro in the cylinder 75 A, the piston being provided with one or more apertures 11. 12 is a valve adapted to be seated against the rear side of the piston 10 and normally held thereagainst by a spring 13, surrounding the piston rod 9, and inter- 80 posed between the valve 12 and the collar 14 on the piston rod.

The suction chamber 15 is provided with a forwardly extending entrance tip 19, carrying a yielding member 20, preferably a 85 non-abrading sleeve adapted for presentation to the surface surrounding an opening, to exhaust foreign matter from the opening into the suction chamber.

The screen 21 is preferably a circular sheet 90 of cloth mounted in a ring structure 22 clamped between the collection receptacle and the head 4 as described.

In the practical use of my vacuum cleaner, the tip 19 is presented to the object to be 95 cleaned, and the piston 10 reciprocated. During the rearward stroke, the spring 13 holds the piston valve 12 closed, thus producing a suction between the piston and the suction valve 6, causing the suction valve to 100 be unseated and air and foreign matter to be drawn through the suction chamber, and air through the screen 21, the diaphragm 5 and the suction valve into the cylinder A. The foreign matter is retained in the suc- 105 tion chamber as only the air passes through the screen. During the forward stroke of the piston the pressure of the air in the cylinder A in front of the piston unseats the piston valve 12 by overcoming the spring 13 110 and drives the suction valve 6 to its seat. The closing of the suction valve prevents a

back draft into the suction chamber and thus prevents a disturbance of the accumulated dirt or other substance which has been collected therein.

5 In Fig. II I have shown my vacuum cleaner as it appears as applied to a tracker bar T, whereby the utility of my device for the cleaning of an article of this description will be readily understood.

10 I claim:

In a vacuum cleaner, a pump mechanism consisting of a cylinder provided with a rear cap having an air vent, and a front head having a counterbore in its rear side adapted to receive the front end of the cylinder,

a counterbore in its front side adapted to receive a screen, an exterior screw-threaded portion adjacent the front side adapted to receive a securing band and, immediately, an interior perforated diaphragm 20 controlled by a spring-seated controlling-valve located on the rear side of the diaphragm; a piston-head located in the rear of the perforated diaphragm and having an opening controlled by a spring-seated valve 25 on the rear side of the piston-head, and a piston-rod extending rearwardly from the piston-head, out through the apertured rear cap and terminating in a handle portion.

EMIL F. WEMHOENER.
